Primary Examiner — Karen E Eldridge Powers

(74) Attorney, Agent, or Firm — Sterne, Kessler,
Goldstein & Fox P.L.L.C.(57) CLAIM

The ornamental design for a type font, as shown and described.

DESCRIPTION

The file of this patent contains at least one drawing/photograph executed in color. Copies of this patent with color drawing(s)/photograph(s) will be provided by the Office upon request and payment of the necessary fee.

FIGS. 1-22 are a face view of a type font showing the claimed design.

1 Claim, 22 Drawing Sheets
(22 of 22 Drawing Sheet(s) Filed in Color)
